A. PLUMP.
RAILROAD SPIKE.
FILED OCT. 18, 1922.

UNITED STATES PATENT OFFICE.

ADOLPH PLUMP, OF REDWOOD CITY, CALIFORNIA.

RAILROAD SPIKE.

Application filed October 18, 1922. Serial No. 595,367.

To all whom it may concern:

Be it known that I, ADOLPH PLUMP, a citizen of the United States, and resident of Redwood City, in the county of San Mateo and State of California, have invented certain new and useful Improvements in Railroad Spikes, of which the following is a specification.

My invention is a railroad spike of the type of construction disclosed in Letters Patent of the United States #1,409,403, granted to me March 14, 1922, and it consists in the combinations, constructions and arrangements herein described and claimed.

In the aforesaid Letters Patent, I disclose a spike adapted for and having means cooperating therewith to lock a spike in driven position against accidental withdrawal from or twisting in the material into which driven.

An object of the present invention is to provide a spike of the character described which is of simplified construction and of generally conventional form, being capable of production in the same manner as an ordinary railroad spike and at a cost no greater than that of the ordinary spike.

A further object of my invention is to provide a spike of the character described which is adapted to be driven into a usual aperture in a tie plate of ordinary construction in an ordinary manner to secure a rail to a tie and which is formed to cooperate with the tie plate to act on a key associated therewith and driven into the tie in such manner that the portion of the key penetrating the tie will be deflected from a plane parallel to the longitudinal axis of the spike and will thus hold the latter against accidental withdrawal or twisting.

A further object of the present invention is to provide a spike construction of the character described in which both the spike and the locking key may be operatively applied and withdrawn through the agency of tools ordinarily used in constructing tracks.

Other objects and advantages will be apparent from the following description, considered in conjunction with the accompanying drawings, forming a part of this application, in which—

Figure 1 is a fragmentary perspective view, showing a portion of a track construction equipped with spikes embodying the present invention,

Figure 2 is a side view of a spike constructed in accordance with the present invention, showing in conjunction therewith a tie plate and a fragmentary portion of the base flange of a rail, the latter being shown in section,

Figure 3 is a vertical section through a spike embodying the invention in applied position in respect to a tie plate and a supporting tie, and

Figure 4 is a top plan view of the spike and of a portion of the base flange of a rail, the locking key shown in the preceding views being omitted to show the position of the lock receiving groove in respect to the edge of the base flange.

Referring now to the drawings, a spike embodying the present invention comprises a shank 1 which is in general of conventional construction and is merged at one end into the usual head 2. As is usual the head 2 is formed with the front marginal portions thereof extending forwardly of the plane of the front side of the shank to overlie a marginal portion of the base flange 3 of a rail 4 which rests upon a wooden tie 5 into which the shank of the spike is driven so that the front side thereof is contiguous or adjacent to the edge of the base flange. In practice, the shank of the spike will be driven through an aperture 6 in a tie plate 7 which is interposed between the upper face of the tie 5 and the rail 4 and upon which the latter rests.

A spike embodying the present invention departs from the conventional in that a groove 8 is provided in one side wall thereof for a purpose to be described, the groove being formed in the spike coincidentally with the forming of the latter and without increasing the cost of manufacture thereof.

The groove 8 is arcuate in longitudinal sectional contour, being deepest intermediate its ends and decreasing regularly in depth from the deepest part thereof toward both ends. The groove 8 extends longitudinally of the spike and is located in such position along the latter that one end of the groove opens through or terminates in the plane of a side wall of the shank at an appreciable distance below the juncture of the shank with the head while the other end of the groove opens through one laterally extending marginal portion of the head 2, as indicated at 9 in Figure 4. The groove 8

is of course open throughout its length and in the present embodiment of the invention the side walls thereof are straight and parallel while the bottom or inner wall thereof is arcuate in cross sectional contour to conform to the contour of a key or locking nail 10 which is provided with a head at one end and is pointed at its other end, as indicated at 12. Obviously, the cross sectional 10 contour of the groove 8 may vary from that described to conform to the contour of keys of different cross sectional contour from that illustrated without departing from the spirit and scope of the invention.

15 The length of the groove 8 is such that the major portion thereof is disposed below the plane of the upper face of the tie plate 7 when the spike is in fully driven position and has been projected through an 20 aperture in the tie plate. A binding action on the locking key 10 therefore takes place at the upper end of the aperture through the tie plate at the point indicated at 13 in Fig. 3 when the key 10 is driven through the 25 groove 8 between the upper edge of the aperture 6 and the inner or bottom wall of the groove. This binding action will cause the inserted end 12 of the key 10 to slide along the inner or bottom wall 8 under the impact 30 of blows delivered upon the head 11 and to be bent or cammed because of the engagement with such wall to penetrate the tie 5 at the one side of the spike so that the end portion 12 will extend substantially 35 in a plane intersecting the longitudinal axis of the shank 1 at right angles when the locking key 10 is in fully driven position. The locking key 10 is made of a material which will bend under stress, 40 and which is softer than the material composing the spike and the tie plate whereby the binding action at 13 will also aid in preventing accidental withdrawal of the locking key 10 and consequently of the spike, 45 although of course the arcuate shape of the fully driven key and the engagement thereof with the tie are important factors in the holding of the locking key against displacement from driven position.

50 In order that the locking key may be conveniently withdrawn, when desired, through the agency of the usual claw-bar, a washer 14 having a convexly curved lower face is slipped over the pointed end of the 55 key against the head 11 before the key 10 is applied in the manner described. A key comprising a large head can be substituted for the key 10 and washer 14.

From the foregoing description of the 60 various parts of the device, the operation thereof may be readily understood. A spike embodying the present invention can be manufactured as cheaply as a spike of conventional construction without the use of 65 any complicated tools and without increase

in cost. The spike is adapted for use in track constructions of the type ordinarily provided in railways at the present time and can be both operatively applied and withdrawn without the use of any special tools. 70

Obviously, my invention is susceptible of embodiment in forms other than that illustrated in the accompanying drawings and I therefore consider as my own all modifications or adaptations of the form of the device disclosed herein which fairly fall within the scope of the appended claims. 75

I claim:—

1. A railroad spike comprising a body 80 consisting of a shank and a head merged into the shank at one end of the latter, said body being formed with a longitudinally extending groove in one side thereof, said groove opening at one end through one side of the head and terminating at its other end 85 in the plane of the same side of the shank at an appreciable distance from the junction of the shank and head.

2. A railroad spike comprising a conventionally shaped body consisting of shank 90 and head portions merged one into the other, said body having in one side thereof a groove opening at one end through one side of the head and extending longitudinally of the body to terminate in the plane of the same 95 side of the shank, said groove being curved in longitudinal sectional contour.

3. A railroad spike comprising a conventionally shaped body consisting of shank and head portions merged one into the other, 100 said body having in one side thereof a groove opening at one end through one side of the head and extending longitudinally of the body to terminate in the plane of the same side of the shank, said groove being 105 arcuately curved in longitudinal sectional contour.

4. In combination, a railroad spike comprising a conventionally shaped body consisting of integral shank and head portions, 110 said body having a groove formed in one side thereof, said groove opening at one end through a side portion of the head and terminating at its opposite end in the plane of the same side of the shank and being formed 115 with the inner wall thereof curved to lie in the arc of a circle, a tie-plate having an aperture through which the body of the spike may be projected so that the major portion of the groove extends below the 120 plane of the upper side of the tie-plate, and a locking key insertible into the groove between the upper edge of the aperture through the tie-plate and the walls of the groove, said locking key being adapted to 125 be bent when driven along the inner wall of the groove in such manner as to be deflected laterally of the body of the spike so that the inserted end portion of the key will lie substantially in a plane extending at right 130

angles to the longitudinal axis of the body of the spike when the spike and key are both in fully driven position.

5. In combination, a railroad spike comprising a conventionally shaped body consisting of integral shank and head portions, said body having a groove formed in one side thereof, said groove opening at one end through a side portion of the head and terminating at its opposite end in the plane of the same side of the shank and being formed with the inner wall thereof curved to lie in the arc of a circle, a tie-plate having an aperture through which the body of the spike 10 may be projected so that the major portion of the groove extends below the plane of the upper side of the tie-plate, a locking key insertible into the groove between the upper edge of the aperture through the tie-plate 15 and the walls of the groove, said locking key being adapted to be bent when driven along 20 the inner wall of the groove in such manner as to be deflected laterally of the body of the spike so that the inserted end 25 portion of the key will lie substantially in a plane extending at right angles to the longitudinal axis of the body of the spike when the spike and key are both in fully driven position, said key having a head at 30 its upper end, and a washer disposed upon the key between the head of the latter and the head of the spike.

6. In combination, a railroad spike comprising a conventionally shaped body consisting of integral shank and head portions, 35 said body having a groove formed in one side thereof, said groove opening at one end through a side portion of the head and terminating at its opposite end in the plane of the same side of the shank and being formed with the inner wall thereof curved to lie in the arc of a circle, a tie-plate having an aperture through which the body of the spike 40 may be projected so that the major portion of the groove extends below the plane of the upper side of the tie-plate, a locking key insertible into the groove between the upper edge of the aperture through the tie-plate and the walls of the groove, said locking key being adapted to be bent when driven along 45 the inner wall of the groove in such manner as to be deflected laterally of the body of the spike so that the inserted end portion of the key will lie substantially in a plane extending at right angles to the longitudinal axis 50 of the body of the spike when the spike and key are both in fully driven position, said key having a head at its upper end, a washer disposed upon the key between the head of the latter and the head of the spike, the face 55 of the washer proximate to the head of the spike being concaved in form.

ADOLPH PLUMP.
